UNITED STATES PATENT OFFICE.

CARL JOKAN JACKSON, OF SUPERIOR, WISCONSIN.

DOOR CONSTRUCTION.

1,251,779.

Specification of Letters Patent. Patented Jan. 1, 1918.

Application filed May 26, 1917. Serial No. 171,164.

To all whom it may concern:

Be it known that I, CARL J. JACKSON, a subject of Norway, residing at Superior, in the county of Douglas and State of Wisconsin, have invented certain new and useful 5 Improvements in Door Constructions, of which the following is a specification.

The invention relates to closure constructions, especially to window constructions in 10 which a movable piece of glass is provided in association with a screen element, whereby when the glass element is moved to permit ventilation the opening will be closed by the screen. In the present particular 15 embodiment, the device is adapted to use in doors, and its simplicity and adaptability to that use is an important advantage of the invention. It is an especial aim of the invention to provide a device of this character 20 which will be peculiarly efficient in effecting the passage of flies outwardly through a window or door opening. To this end, it is an aim to provide a means whereby the upper edge of the glass will be presented at 25 the lower part of an opening in such a manner that flies alighting upon the inner side of the glass will be free to crawl completely to the upper edge thereof and take flight therefrom from the exterior of the house. 30 At the same time it is a purpose to effect the ample support of the upper edge of the glass when the device is closed, and to provide a good wind-tight joint between the frame opening and the glass. In connection with 35 this it is also desired to secure the screen in such relation to the glass that ample ventilation will be secured with a practical elimination of liability of ingress of flies.

It is also an aim to completely clear the 40 window opening of the screen when the glass is in closed position.

An additional purpose is to provide a desirable construction in a door for the uses indicated.

I am aware that screens have been connected to the upper edge of window sash elements or the like in such a manner that when the glass is in lowered position the screen will be drawn downwardly, and when 45 raised the screen will be moved above the opening, and I do not claim broadly this idea, except wherein parts are constructed or associated in the same relation as herein-after claimed.

Additional objects, advantages and features of invention will appear in the con-

struction, arrangement and combination of parts comprising one of the possible embodiments of the invention, as hereinafter described and shown in the drawings, 60 wherein,

Figure 1 is a front elevational view of the device in closed position,

Fig. 2 is a similar view of the device open 65 for ventilation,

Fig. 3 is a rear view of the device partly closed, with a portion of the casing removed,

Fig. 4 is a vertical sectional view,

Fig. 5 is a horizontal sectional view on line 5—5 of Fig. 2, 70

Fig. 6 is a detail of the mounting of the sliding sash,

Fig. 7 is a detail of the screen structure as arranged in the sliding sash,

Fig. 8 is a horizontal section at the upper 75 part of the device when closed, on line 8—8 of Fig. 1.

There is illustrated a door 10, adapted to be mounted in any ordinary door frame and to be provided with the usual lock and 80 knob construction, the last named details not being illustrated, as forming no peculiar part of such invention. The door 10 in the present instance comprises the stiles 11 of simple form at each side, rectangular in cross 85 section, between which the top and bottom rails 12 and 13 are mounted. Casing portions 15 and 14 are mounted on the foregoing parts, at the inner and outer sides of the door respectively, forming a suitable space 90 within the door for a sliding sash element 16 to be described. The sash 16 comprises a bottom piece 17, and two uprights 18 of similar form and construction, these three parts being suitably grooved on the inner 95 sides to receive a pane of glass 19 which stops short of the upper end of the uprights 18 a considerable distance, the measure of which depends upon the manner in which the door is to be used. The groove 100 for the glass is located nearest to the front side of the door, leaving a considerable portion of the sash frame projecting toward the inner side of the door. Intermediately of the height of the sash frame, suitable spring- 105 pressed pins 20 are mounted having end portions projecting outwardly from the sash in each direction to engage alternatively in a series of openings 21 formed in the stiles 11, and if desired a groove 22 may also be 110 formed in the stiles next adjacent the sash and alined with the pins 20 so that it is not

necessary for the pins to be completely retracted in order to free the sash for vertical adjustment. The pins 20 have handle portions 23 projected inwardly before the glass, 5 and suitably formed to be used to draw the pins and also to serve as handles to move the sash. The upper ends of the uprights 18 of the sash are formed in any suitable manner with a kerf 24, extending a distance below the upper edge of the glass before mentioned, and the kerf extends approximately 10 in a plane parallel to the glass and close to the inner side of the sash, so that the kerf is spaced approximately one-half inch from 15 the glass. Set in the kerf there is a portion of screen material 25 snugly engaged between the uprights 18, being rectangular in form, and having its upper and lateral edges flush with the ends and sides of the uprights 20, while its lower edge extends horizontally, 25 being engaged to the full inner ends of the kerf 24 before mentioned. The screen is preferably cut so that the woven edge 26 will be presented downwardly, reducing the liability of the fraying of the screen. The screen is utilized to hold the sash frame in proper form after engagement of the glass therein, and is secured in place by engaging a number of screws 27 through the material 30 of the uprights 18, centrally thereof at the inner side, the screws being slidable in the inner material beside the kerf, and snugly screwed into the wood before the screen. It is also to be noted that the kerf at each side 35 is slightly widened toward the outer side of the upright 18, so that the screen will be pinched between the opposite portions of the upright closely adjacent the inner edge of the upright, forming a snug fit. If desired, 40 the upper edge of the screen may be protected by a suitable metal edging 28, in the form of a strip bent upon a longitudinal medial line so that its opposite side portions bear against the opposite sides of the screen, the upper 45 edge of which is set snugly in the fold of the metal. It is undesirable that this metal edging be located at the lower edge of the screen, as it would tend to induce flies to leave the glass, at times, and crawl upon the inner side 50 of the screen, from which they would tend to pass into the house. In each casing portion a window opening 29 is formed, having a vertical dimension considerably less than the vertical dimension of the space between 55 the top and bottom rails of the door, and preferably less in width than the space between the uprights 18 of the sash. The glass 19 is of a height slightly greater than the height of the opening 29, so that when the 60 sliding sash is in its uppermost position, with the bottom 17 immediately under the opening 29, the glass will extend above the upper side of the opening. The frame 16 is of such size that when in the last mentioned position the uprights 18 extend into

close relation with the top rail 12 of the door. One of the recesses 21 in each stile of the door is at such a level as to engage a respective pin 20 to hold the sash in this raised position. In the present instance, 70 the space within the door is such that when the sash 16 is at the lower limit of its movement the screen 25 extends slightly above the opening 29, although this is not absolutely essential, as the recess 22 may be suitably positioned in the stiles of the door to engage the pins 20 to hold the sash in proper position when lowered. The grooves 22 may also be utilized as a limiting means and the pins constructed so that they cannot be 80 fully withdrawn at both sides, in any well known way. In the upper part of the door, upon the inner side of the casing section 14, there is provided a guard piece 31, of a width to fit snugly between the uprights 18 85 of the sash, and having a sufficient thickness to engage closely against the outer side of the screen 25, or very close thereto as found most desirable. The lower edge of the element 31 is grooved to receive the upper edge 90 of the glass 19 snugly therein, and a small projection may be formed above this groove, as at 32 to engage in the glass holding grooves of the uprights 18 to form a snug joint around the glass, preventing ingress of 95 air in objectionable quantities, when the sash 16 is raised.

With this device satisfactory ventilation may be obtained through doors while closed, and the device operates as a trap means, at 100 least to the extent of permitting ready escape of flies alighting upon the glass when they follow their natural tendency to crawl upwardly toward light, and in having an opposing effect upon flies without the door, 105 since flies do not tend to crawl downwardly into dark places. The space 33 between the upper edge of the glass 19 and the lower edge portion of the screen 25 may be termed a slot. When the sash 16 is in closed position, should there be any flies upon the screen 25, these will be caused by the piece 31 to take flight from the screen through the upper part of the opening 29 as the sash is raised, until the opening is closed by the 115 glass 19.

It will be seen that a very simple construction of closure and fly guard is provided adapted to be manufactured at a low cost and used readily by the general public 120 without difficulty.

In the event that the glass 19 becomes broken, in order to replace it with a new piece, the casing piece 14 or 15 is removed, the sliding sash taken out, and the screws 27 125 removed at one side, after which a piece of glass adapted to fit snugly in the grooves of the uprights 18 when in parallel relation, the broken pieces of glass removed and the new pane slipped into place. The screen is then 130

drawn taut again and the loosened screws secured in place to hold the screen taut, and the parts replaced in proper order.

What is claimed:

- 5 1. A casing having a window opening therein, a sliding sash within the casing comprising a bottom piece and two uprights, a pane of glass between the uprights having its upper edge portion intermediately of the
- 10 sash, a screen carried between the uprights in a plane parallel to the glass and fixed with its lower edge in spaced partial overlapped relation therewith, said sash being movable to present the glass over the whole
- 15 of said window opening, at one position, to dispose the screen before the opening and to leave a clear way in the opening above the glass at another position, said casing including an element adapted to fit snugly between
- 20 said uprights of the sash and between the screen and glass, and means to releasably secure the sash in raised position
2. A door construction comprising stiles and rails, casing elements mounted thereon to form a housing and having aligned window openings therethrough intermediately of the height of the housing, a sliding sash in the door having a pane of glass adapted to close said openings when in one position,
- 25 30 said sash having a clear way therein over the upper edge of the glass for a distance, a screen carried by the sash across said clear way and spaced inwardly of the glass in overlapped relation, and means to hold the
- 35 sash in raised position.
3. In a sash of the character described a bottom cross piece, uprights at each end thereof, a pane of glass set in the cross piece and uprights closely adjacent the outer side
- 40 of the sash, said uprights extending a distance above the glass, and a portion of

screen material of the character described secured between the uprights extending in parallel relation to the plane of the glass from a distance slightly below the upper 45 edge of the glass to the upper part of the uprights.

4. In a sash of the character described a bottom cross piece, uprights at each end thereof, a pane of glass set in the cross piece 50 and uprights closely adjacent the outer side of the sash, said uprights extending a distance above the glass, and a portion of screen material secured between the uprights extending in spaced parallel relation 55 to the plane of the glass from a distance slightly below the upper edge of the glass to the upper part of the uprights, said screen material being under tension between the uprights to hold them in snug compressing 60 engagement with the glass whereby the sash frame is stiffened without requiring a top rail.

5. In a sash of the character described, a bottom cross piece and uprights, a pane of 65 glass set in the cross piece and uprights having an uncovered upper edge portion stopping short of the upper end of the uprights, said uprights having kerfs therethrough in a plane parallel to the glass and spaced inwardly thereof, extending from below the upper edge of the glass, a portion of screen material set in the kerf, and screws engaged across the kerfs and in the material of the uprights on each side thereof to clamp the 70 75 screen as described.

In testimony whereof I have affixed my signature in presence of two witnesses.

CARL JOKAN JACKSON.
